Inventor.

UNITED STATES PATENT OFFICE.

JOSIAH B. GATHRIGHT, OF LOUISVILLE, KENTUCKY.

FASTENER FOR STRAPS.

SPECIFICATION forming part of Letters Patent No. 251,776, dated January 3, 1882.

Application filed March 21, 1881. (No model.)

To all whom it may concern:

Be it known that I, JOSIAH B. GATHRIGHT, a citizen of the United States, residing at Louisville, in the county of Jefferson and State of Kentucky, have invented certain new and useful Improvements in Strap-Fasteners; and I do hereby declare the following to be a full, clear, and exact description of the invention, such as will enable others skilled in the art to 10 which it appertains to make and use the same, reference being had to the accompanying drawing, and to the letters or figures of reference marked thereon, which forms a part of this specification.

15 My invention consists in an improved form of cast-metal jaws for securing straps and the adaptation of the same for use with rings, buckles, &c., when not cast as a part of them.

The drawing shows my improved fastener 20 cast as a projection from or in one piece with an ordinary buckle. It may also be cast separately from the buckle and be adapted to loop about a bar of the buckle.

The fastener is composed of an upper and 25 lower jaw, solidly connected at one end and open at the other, one of the jaws, A, being in the form an open frame, the central opening in it being large enough to allow the other jaw,

B, to be cast through it, thus avoiding the necessity of coring in casting the device.

A loop, E, is cast upon the end of one of the jaws, as seen in the drawing, and serves to hold down the end of the buckled strap. The device may be constructed without this loop when intended to be used with three-bar buckles. A 35 slot, K, centrally in the connected ends of the jaws accommodates the tongue of the buckle.

One or both jaws should be toothed, so that when a strap is inserted between them and the jaws forced to clamp it the teeth will penetrate the leather and hold it securely.

What I claim as new, and desire to secure by Letters Patent, is—

1. A cast-metal strap-fastener constructed with two jaws, A and B, one of which is in 45 skeleton form and one or both toothed, as and for the purpose specified.

2. A metal strap-fastener composed of jaws A and B, one of which is provided with a loop, E, as and for the purpose specified.

In testimony whereof I have set my hand this 30th day of December, 1880.

JOSIAH B. GATHRIGHT.

Attest:

JOHN J. HARBISON,
G. W. BRADEN.
